DESIGN FOR A MONOGRAM FRAME

Michael Chernow, Brooklyn, N. Y., assignor to
Service Patents Corporation, a corporation of
New York

Application May 16, 1935, Serial No. 56,854

Term of patent 7 years

To all whom it may concern:

Be it known that I, Michael Chernow, a citizen of the United States and residing at Brooklyn, in the county of Kings and State of New York, have invented a new, original, and ornamental Design for a Monogram Frame, of which the following is a specification, reference being had to the accompanying drawing, forming part thereof, and in which

Fig. 1 is a top plan view of the monogram frame showing my design, and

Fig. 2 is an end elevational view thereof.

The monogram frame comprises an outer gen-

erally square frame element and an inner generally square frame element of smaller dimensions, equi-distant from the outer frame element at each side to afford a general rectangular framing opening about the inner frame element and within the outer frame element, and a plurality of short bridge elements joining the corresponding lateral edges of the two frame elements.

I claim:

The ornamental design for a monogram frame, substantially as shown and described.

MICHAEL CHERNOW.
